DESIGN FOR A SEWING MACHINE HEAD

Raymond F. List, Belvidere, Ill., assignor to National Sewing Machine Company, Belvidere,
Ill., a corporation of Illinois

Application March 22, 1934, Serial No. 51,145

Term of patent 3½ years

To all whom it may concern:

Be it known that I, RAYMOND F. LIST, a citizen of the United States, residing at Belvidere, in the county of Boone and State of Illinois, have invented a new, original, and ornamental Design for a Sewing Machine Head, of which the following is a specification, reference being had to the accompanying drawings, forming part thereof:

In the drawings:—

Fig. 1 is a rear elevation of the sewing machine head embodying my new design and in which the conventional portions of the head are shown in dotted lines; the horizontal arm portion shown in full lines comprising the dominant features of the present invention;

Fig. 2 is an enlarged plan view of the horizontal arm portion of the head showing in full lines the dominant features of the design shown in Fig. 1; and

Fig. 3 is a view similar to Fig. 2 as it would appear from the bottom of the horizontal arm portion.

I claim:—

The ornamental design for a sewing machine head as shown and described.

RAYMOND F. LIST.
